UNITED STATES PATENT OFFICE.

CALEB V. FLEETWOOD, OF CLEVES, OHIO.

PETROLEUM-BURNER.

SPECIFICATION forming part of Letters Patent No. 392,022, dated October 30, 1888.

Application filed January 23, 1888. Serial No. 261,704. (No model.)

To all whom it may concern:

Be it known that I, CALEB V. FLEETWOOD, of Cleves, in the county of Hamilton and State of Ohio, have invented a new and useful Improvement in Petroleum-Burners, which improvement is fully set forth in the following specification and accompanying drawings, in which—

Figure 1 is a perspective view, partly in section, of a stove equipped with my petroleum-burner. Fig. 2 is a side view of the burner removed from the stove; Fig. 3, a perspective view of the intermediate reservoir for supplying petroleum to the burner; and Fig. 4, enlarged, a perspective view of the hinged reticulated pad or partition for the fire-chamber of the burner.

The object of this invention is to provide a petroleum-burner. Although it can be used in stoves of all kinds, and is also applicable to furnaces and boilers, I have especially arranged it, as herein shown, for cooking stoves, and an examination of the principles involved will show its ready adaptability for stoves and furnaces.

My invention consists in providing the ordinary fire-box of a stove with a V-shaped metal trough, the rear end of which extends up the rear fire-wall and the front wing projects forward to the front wall of the stove. The trough has shallow end pieces, so as to enable it to retain a certain amount of oil, and this trough is supplied with oil by means of a pipe centrally attached to the base of this trough, which leads to a reservoir located in the fire-box of the stove directly forward of this trough. Above the V-shaped trough, a short distance forward of its center, is a partition which inclines forwardly, and the lower end of which terminates at a suitable point above the trough. On the front side of this partition, near its base, is hinged a gate, the forward end of which swings against the inclined side of the V-shaped trough. On the rear side of this partition is a ledge to receive a horizontally-disposed reticulated partition, the rear edge of which is hinged against the inclined rear wall of the trough, for purposes which will now be specifically set out.

I have found by experimenting with petroleum as a fuel that while absorbents—such as

mineral wool, asbestos, and other non-combustible fibrous materials—are often serviceable for the purpose of making a fire-bed, it is essential that this material must be constantly renewed or changed, so as to obviate the great liability of clogging. I also find that where a bed is used the atmosphere does not properly commingle with the carbonic gases formed by the heat; hence smoke and soot is the result. For cooking-stoves especially it is necessary that the flame should be as white as possible and not capable of generating or depositing soot. I accomplish this by the following mechanism:

The stove shown in the accompanying drawings is of the ordinary kind where the combustion-chamber extends across the forward end of the stove, and in applying my burner the grate of the stove is removed. The burner is composed of a V-shaped trough, the rear wing, A, of which extends up alongside of the rear fire-wall, B, of the stove, while the front wing, C, extends forward to the front wall, D, of the stove. The trough proper, as shown at E, is designed to hold the petroleum, and has end pieces, F, integral with the wings A C. It will be observed that the rear wing, A, is nearly vertical, while the front wing is more nearly in a horizontal position.

In the space below the front wing, C, is located a triangular-shaped reservoir, G, the rear tapering end of which has a pipe, H, by means of which connection is made with the base of the trough E midway between the ends. This reservoir is also connected with the main reservoir I on the rear end of the stove by means of a pipe, J. A suitable cock, K, is located in this pipe, so as to regulate the flow of the fluid. The front end of the reservoir G has an opening, L, supplied with a glass, and on the side of the opening is a scale, by which means the quantity of oil in the reservoir can be noted and measured. It will be observed that the reservoir G is so located that the base of the reservoir is only slightly lower than the bottom of the trough E. When, therefore, the petroleum fills the reservoir to the dotted line M, the oil will rise to the same level in the trough, and as it gradually consumes, the oil passes through the pipe H until all the petroleum in the trough is exhausted, and only a

small amount remains in the bottom of the reservoir.

The trough E is V-shaped for a particular purpose. When it is filled with petroleum, it exposes to the flame a large surface. When, however, it is only partially filled, there is less oil-surface proportionately, and by regulating the inflow to the reservoir G by means of the cock K any desired degree of heat may be produced. The door M' in the front part of the stove can be opened to expose the reservoir G.

Above the V-shaped trough and a little forward of the center of the trough is the lower dependent end of the partition N. This partition also extends from one end of the fire box to the other, and its ends are secured to the end walls of the fire-box of the stove, or in such a manner thereto as not to permit air to pass from one side of the partition to the other. The lower end terminates at a point slightly above the end pieces, F, of the trough, while the angle or inclination of the upper end of the partition is toward the front, the extreme upper end being curved and made to fit against the top of the stove. The lower end of this partition has on its rear side a ledge, O, and directly across from this on a horizontal line is a partition, P, hinged either to the inclined wing A or to the sides of the stove, so that it will turn down with its forward end resting on the ledge O. As shown in Fig. 4, the rod Q, to which the partition P is attached, projects at each end, and one of the ends is equipped with a right angled extension, R, which is on the outside of the stove, and by means of which the partition P can be turned up or down. The object of this hinged partition is as follows: The trough E is the initial combustion-chamber for the crude oil, the air for supplying the combustion being received through the space between the lower end of the vertical partition N and the front wing of the trough. After the heat has reached a certain point (the hinged partition P being in the meanwhile turned up, as shown in Fig. 2) the partition is turned down, as shown in Fig. 1. The same quantity of air continues to flow in below the partition N, or an additional amount may be turned on and thereby supply a greater amount of nitrogen gas to the carbonic product generated by the heat below the partition P. The partition P being composed, preferably, of loosely woven asbestos cloth, or of any other reticulated incombustible material, acts as a

momentary retainer of the gases, and as they issue through this reticulated partition they ignite above the partition and produce a clear bright flame of great temperature and admirably adapted for cooking-stoves. The reticulated partition must be very loosely woven, so the gases can readily pass through; but as it would be difficult without experiment in each case to state the quantity I cannot be more specific as to the manner of constructing it.

On the front side of the vertical partition, near its lower end, is hinged a gate, S, the front edge of which rests on the inclined wing C. A rod, T, which extends down the inclined wing, has its lower curved end resting under the gate S, so that it may be raised or moved to or from the plate C at will. By this means the flow of air to the combustion-chamber below the horizontal partition P is regulated. It will be observed, therefore, that the combustion-chamber is practically divided horizontally into two compartments, the compartment below the partition being the initial combustion-chamber, while the part above the partition is the prime or heating chamber for the stove.

What I claim as new is—

1. A burner for the fire-box of a stove, composed of a V-shaped trough, in combination with a central vertically-disposed permanent partition, and on its forward side an adjustable gate for regulating the inflow of air, and the oil-supply tank, substantially as herein set forth.

2. The combination of the V-shaped combustion-trough, the reservoir and connecting-pipes, the vertically-disposed partition above the trough, and the hinged reticulated horizontal partition on one side and the hinged adjustable gate on the other side thereof, substantially as herein set forth.

3. The combination of the V-shaped trough, composed of the rear wing, A, and the forward wing, C, the partition dependent in said trough and having a ledge, O, on its rear side, combined with hinged partition P, adapted to rest in its horizontal position on said ledge, and the reservoir G, substantially as described.

In testimony that I claim the foregoing I have hereunto set my hand, this 20th day of January, 1888, in the presence of two witnesses.

C. V. FLEETWOOD.
